VACUUM SEAL INDICATOR

Thomas S. J. Richards, Glendale, Calif., assignor
to Don Baxter, Inc., a corporation of Nevada

Application November 6, 1935, Serial No. 48,575

2 Claims.

(Cl. 220—44)

This invention relates to a vacuum seal indicator and is particularly useful in connection with canned foods and other products as an indicator of the sterility or condition of the contents of the can.

In the manufacture and sale of foods and other products in vacuum cans it sometimes happens that a can has a tiny opening through the sealing metal or some other part of the can and through which air enters the can. The development of bacteria, etc., inside the can results in spoiling the food. And while sometimes the bacteria develops sufficient pressure to bulge one end of the can, it often happens that there is no visual indication which enables the purchaser or seller to determine the condition of the contents. Also, it sometimes happens that the end of a can is pressed outward in the filling operation and the bulge of a can does not mean that the content of the can is spoiled.

The specific purpose of the present invention is to provide simple means for determining without fail the condition of the contents of the can. A more specific object is to provide means which cannot help but draw the attention of the purchaser and the seller to a can which has its contents contaminated by bacteria, yeast, etc.

The invention is illustrated, in one embodiment by the accompanying drawing, in which—

Fig. 1 is a plan view of a can equipped with a seal indicator embodying my invention; Fig. 2, a plan detail view of the removable seal indicator; Fig. 3, a plan detail view of a sealing ring employed; and Fig. 4, a broken sectional view, the section being taken as indicated at line 4 of Fig. 1.

The invention may be employed with any type of can. In the illustration given, a circular can A is shown having its top sealed with a cover A'. The cover or lid A' is preferable dished in its central portion 10 and apertured at 11. The edge portion 12 surrounding aperture 11 is preferably flared up in the manner indicated more clearly in Fig. 4. A flexible sealing ring 13 of rubber or other suitable resilient material is placed about the flange or edge 12. For the purpose of providing a tight seal, I prefer to employ for the sealing ring 13 a gum rubber or other material which has a tendency to form an air tight connection between the parts.

Over the seal 13, I place the indicator cap 14. The cap 14 is provided centrally with a downwardly extending central neck 15 which passes through the aperture and has a bottom substantially in line with the bottom wall of the de-

pression 16. The cap 14 is also provided with an outwardly and downwardly extending flange 16, the outer or lower edge of which approaches but does not extend to the depressed wall 10 of lid A'.

While in the specific description given, I have shown a relatively small aperture in the wall 10 and a relatively small cap 14 covering the aperture, it will be understood that the opening may be made much larger and the cap made correspondingly larger; and for certain purposes, as when the can is used in connection with certain types of foods or products this may be desirable. On the other hand, it may be desirable in connection with certain products, to greatly reduce the size of the opening from that illustrated and correspondingly the size of the cap. Also, the location of the indicator device may be changed from the top of the can to any other suitable surface, a suitable recess being provided to protect the indicator from dislocation. Normally, it will be more suitable for the indicator to be located at the top of the can because the cans are placed in an upright position on the shelves, in boxes, etc., and there is less tendency for the indicator cap to be struck.

In the operation of the device, the can may be filled and evacuated in the usual way either by directly drawing a vacuum or by filling the can while the contents are hot. The sealing cap having been placed in position as shown more clearly in Fig. 4, an air tight sealing is formed as the contents of the can cool and the pressure therein is reduced. The differential of pressure between the atmospheric pressure on the outside of the can and the reduced pressure within the can causes the flange 16 of indicator cap 14 to be tightly pressed against the soft rubber seal 13. If the can does not permit the inflow of air into its interior, the pressure within the can will remain sub-atmospheric and the indicator cap will remain in effective sealing position. If air should leak into the can and bacteria should develop therein, the pressure within the can would increase to the point where the pressure within the can was equal to or greater than the pressure outside and under these conditions, the indicator cap 14 would become loose and would fall off when the can was handled. In other words, the sealing cap would indicate positively the condition of the contents of the can. As long as the contents were in good condition, the small indicator seal would remain firmly in position and the can could be handled just as an ordinary can.

The recess surrounding the indicator cap provides ample protection against displacement of the cap. The moment, however, that the contents of the can became spoiled, the indicator cap would be pushed off or would fall off when the can was handled.

While in the foregoing description I have set out one specific method of forming the indicator seal, it will be understood that many other methods may be employed while utilizing the invention and many changes may be made in the shape, size and location of the indicator device without departing from the spirit of my invention. Thus, by way of example: the relative proportions of the cover A' and cap 14 may be changed so as to cause the side wall of depression 10 to extend close to the marginal edge of cap 14, to minimize possibility of accidental dislodgment of the cap, and the top of cap 14 to extend substantially flush with the marginal edge portion of cover A' whereby the cap 14 would contact with the bottom of a can above it or the top of the shipping case, thus insuring the holding of the cap 14 in position on the can in case the vacuum is lost and preventing leakage and damage to other cans.

The foregoing detailed description has been given for clearness of understanding only, and no unnecessary limitations should be understood therefrom, but the appended claims should be construed as broadly as permissible, in view of the prior art.

I claim:

1. A sealed package of contents susceptible of bacterial action, said package being maintained normally under vacuum, comprising a container having one of its walls provided with a well and with an annular flat surface portion extending about said well, the bottom wall of said well being provided with a relatively small aperture, a sealing ring extending about said aperture, and a vacuum-indicator cap extending over said aperture and engaging said sealing ring, said cap being provided with a reduced neck portion extending into said aperture, but being smaller in diameter than said aperture to permit free vertical movement of the cap but substantially preventing lateral movement thereof.

2. In combination with a vacuum container adapted for the storage of contents susceptible of bacterial action producing a spoilage of the contents, said container having a relatively deep well provided with a relatively small aperture in the bottom wall thereof, said container having an annular flange portion extending about said well, a resilient sealing ring about said aperture, a vacuum-indicator cap engaging said ring enclosing said aperture, said cap and said container being provided with interlocking elements whereby vertical movement of the cap is permitted but lateral movement thereof is substantially prevented.

THOMAS S. J. RICHARDS.
